UNITED STATES PATENT OFFICE.

JAY F. BUTLER, OF BROOKLYN, AND URIAH McCCLINCHIE, OF NEW YORK, N. Y.

CANOPY-SUPPORT FOR CHILDREN'S CARRIAGES.

SPECIFICATION forming part of Letters Patent No. 275,582, dated April 10, 1883.

Application filed January 16, 1883. (No model.)

To all whom it may concern:

Be it known that we, JAY F. BUTLER, a citizen of the United States, residing at Brooklyn, in the county of Kings and State of New York, and URIAH McCCLINCHIE, a citizen of the United States, residing at New York, in the county and State of New York, have invented new and useful Improvements in Clamps for Supporting Canopies of Children's Carriages, of which the following is a specification.

Our invention relates to clamps for supporting canopies for children's carriages; and it consists in a pivotally-adjustable clamp attached to the supporting-staff, said clamp having an eye to admit the ball upon the staff end of the canopy, with an embracing device pivoted to said clamp and adapted to clasp the neck of the canopy-staff below the ball, and thereby hold the canopy in place, said canopy being attachable to and detachable from the clamp without removing the latter from the supporting-staff.

Referring to the drawings, Figure 1 is a plan view, showing the clamp attached to the supporting-staff, the enlarged end of the canopy-top stick being shown in broken lines. Fig. 2 is a side elevation. Fig. 3 is an end elevation, taken from the rear, showing the method of attaching and detaching the clamp. Fig. 4 is plan view, showing a preferred form of the device illustrated in Fig. 1, the locking device being shown in engagement with the canopy-staff by full lines and thrown back out of engagement by broken lines.

A in said drawings indicates that portion of the clamp which is attached to the supporting-staff of the carriage. It consists of a single strip of metal bent into the enlarged circular portion *b*, which is of sufficient size to permit the passage of the ball upon the canopy-staff, from which points the ends *A' A'* of the strip extend in substantial parallelism a suitable distance, and are provided with a bolt, *B*, passing through perforations in their extremities. This bolt has a thumb-nut, *C*, by which the clamp may be attached to a tongue formed upon the supporting-staff in the manner described in Letters Patent No. 260,530, granted to us the 4th day of July, 1882.

D indicates the canopy-staff holder, consisting of two elastic leaves, *E E*, which are piv-

oted at one end upon the bolt *B*, and extend thence forward between the leaves *A' A'* of the clamp *A*. These elastic pieces are united by a rivet, *a*, placed a short distance in advance of the bolt *B*, and from this point they slightly diverge until they enter the eye or enlarged circular portion *b*. The leaves *E E* are then bent into a form approaching each a 60 semicircle concentric with the enlarged circular space *b*, but having a smaller diameter of such dimension as to embrace the neck of the canopy-staff beneath the ball. From this point the ends *e e* of the leaves *E E* are carried forward a short distance beyond the limits of the enlarged circular portion *b*. In the lower edge of the circular portion *b*, and directly above the ends *e e* of the canopy-clamp, is formed an open slot, *d*, Fig. 3, adapted to receive and confine the said projecting ends of the leaves *E E*. These leaves are so constructed as to spring apart a short distance when released from said slot, and thereby permit their withdrawal from engagement with the neck of the 75 canopy-staff.

The engagement and disengagement of the clamp is effected in the following manner: After slightly loosening the thumb-nut *C* the part *A* is thrown upward, turning upon the 80 pivot-bolt *B* in the manner shown in Fig. 2, thereby releasing the ends *e e* of the canopy-clamp *D* from their engagement with the slot *d* in the part *A*. As soon as the latter clears the top of the ball on the canopy-staff the 85 neck of the latter may be released by simply drawing it out between the separated ends *e e* of the clamp *D*. The adjustment of the canopy is effected by a reversal of this operation, the neck of the staff being pushed between the 90 open ends *e e* until it enters the circular space *e'*. The part *A* is then turned down over the ball *F* upon the end of the canopy-staff, and the ends *e e* of the clamp *D* are then pressed together and pushed into the slot *d*, where 95 they are retained by the elasticity of the leaves *E E*, which cause the ends *e e* to press against the edges of the slot *d* and create sufficient friction to retain them in the slot.

Instead of the construction described, we prefer the form of clamp shown in Fig. 4. In this form, instead of the two-leaved clamp above described, we construct the device in the following manner: *A''* indicates the clamp, which

is fastened to the supporting-staff in the same manner substantially as that already described in connection with the clamp A. B' is the enlarged circular portion, of such size as to permit the passage of the ball on the canopy-staff, and opening out of this circular space is a throat, C', of such size as to receive the neck of the canopy-staff beneath the ball. D' indicates the locking device, which consists of a yoke having its ends journaled or pivoted in the leaves of the clamp A" and adapted to turn freely into either of two positions shown in solid and broken lines, Fig. 4. Recesses f/f' are formed in the upper edges of the metal forming the throat, to receive the transverse bar d of the locking-yoke D'. This bar is slightly curved backward, so as to form, in connection with the closed end of the throat C', an approximately circular space. The lateral bars of the yoke D' are formed with two parallel or even slightly converging portions, i i, which bear against the outer surfaces of the metal leaves forming the open end of the throat C', thereby giving sufficient friction to hold the yoke in position. Even, however, should this feature be omitted the ball upon the end of the canopy-staff will prevent the opening of the yoke, and thereby retain the neck of said staff in place. By the construction thus shown and described we provide a simple, efficient, and inexpensive locking-clamp or support for the canopy of children's carriages by which the canopy may be easily and quickly attached and detached and held with perfect security in any position in which the support is placed by turning the locking-piece up and down upon its at-

taching-bolt B or upon its pivoted bearings in the supporting-piece. The latter form of construction is preferred, as shown in Fig. 4, as being the most simple, the cheapest, and at the same time equally effective with the device shown in Fig. 1.

Having thus described our invention, what we claim is—

1. A canopy-support for children's carriages, consisting of a supporting-piece adapted to be attached to the carriage-staff and a swinging clamp or lock engaging with said supporting-piece and holding the neck of the canopy-staff, substantially as described.

2. The combination, with the supporting-piece having an enlarged portion through which the ball on the canopy-staff may pass, of a clamp or lock pivoted upon the supporting-piece and adapted to engage with the neck of the canopy-staff, substantially as described.

3. The combination, with the supporting-piece provided with a contracted forwardly-extending space of such size as to permit the entrance of the neck of the canopy-staff, of a locking-piece pivoted upon said support and adapted to close the open end thereof to lock the canopy in place, substantially as described.

In testimony whereof we have hereunto set our hands in the presence of two subscribing witnesses.

JAY F. BUTLER.
URIAH McCLINCHIE.
